184,829

VACUUM CLEANER FOR AUTOMOBILES OR THE LIKE

Lawrence F. Nerheim, Seattle, Wash.

Application March 24, 1958, Serial No. 50,162

Term of patent 14 years

(Cl. D9—2)

Fig. 1

Fig. 2

Fig. 3

Fig. 1 is a perspective view of a vacuum cleaner for automobiles or the like embodying my new design, with the cord fragmentarily shown for convenience of illustration only;

Fig. 2 is a top plan view thereof; and

Fig. 3 is an end elevational view thereof taken from the right of Fig. 2.

I claim:

The ornamental design for a vacuum cleaner for automobiles or the like, as shown.
